NORBERT SCHREIBER, OF LINCOLN, ILLINOIS, ASSIGNOR OF FORTY-NINE ONE-HUNDREDTHREE TO RAPHAEL ROSENTHAL, OF LINCOLN, ILLINOIS.

BOILER-CLEANER.

1,109,550.

Specification of Letters Patent.

Patented Sept. 1, 1914.

Application filed October 23, 1912. Serial No. 727,401.

To all whom it may concern:

Be it known that I, NORBERT SCHREIBER, a citizen of Germany, residing at Lincoln, in the county of Logan and State of Illinois, have invented certain new and useful Improvements in Boiler-Cleaners, of which the following is a specification.

This invention relates to improvements in automatic boiler cleaners; and its object is to provide a device of this class that is applicable to any steam boiler, and that will automatically remove any scum or foam or other impurities from the surface of the water, within the boiler, before the same may have a chance to harden and form a scale; and with the foregoing and other objects in view, the invention consists in the combination and arrangement of parts to be hereinafter fully described in the following specification, pointed out in the claims and illustrated in the accompanying drawings which form a part of the specification, and in which—

Figure 1 illustrates a section of a steam boiler showing the application of my automatic cleaner, and Fig. 2 is a horizontal section on line 2—2 of Fig. 1.

Like reference characters indicate corresponding parts throughout the several views. As thus illustrated 1 indicates the boiler and 2 the surface of the water within the same. Through a suitable opening in the boiler a tap 3 is inserted that may be provided upon its exterior portion with a suitable faucet or other regulating means 4. To the interior end of the tap a flexible tube 5 is secured to the opposite termination of which a spider 6 is secured that is provided with a plurality of tube-arms 7 each of which registers with a circular intake pipe 8 provided with a plurality of apertures 9 through which the scum or other impurities upon the surface of the water may enter and so be drained off through the arms 7, spider 6, flexible tube 5 and the tap. The upper end of the spider is provided with an extension 10 that connects it with a float 11 the buoyancy of which keeps the intake slots 9 at the surface of the water at all times.

The pipe 5 may be of any suitable length, depending upon the size and character of the boiler. In any event, however, this pipe 5 has sufficient flexibility to permit the float 11 and ring 8 to remain horizontal when the water rises and falls, and regardless of

the position of the boiler. The horizontal slots 9 must remain exactly horizontal, and approximately at the surface of the water, if the apparatus is to work in the required manner. Some boilers, such as locomotive, traction and marine boilers, are subject to changes of position during use, and with my invention the intakes 9 are always in operative position, even when the boiler rocks around, and also when the water rises and falls.

I do not limit myself to any particular construction, as the float, etc., may be of any suitable form, and the pipe 5 may be of any suitable character, without departing from the spirit of my invention.

What is claimed is:—

1. A boiler blow-off and cleaner comprising a float having an intake at the surface of the water, and an outlet connection for said float, serving to maintain said float in horizontal position at the surface of the water, during the ordinary rise and fall of the water, and for all positions of the boiler.

2. A boiler blow-off and cleaner comprising a float having an intake at the surface of the water, and an outlet connection for said float, serving to maintain said float in horizontal position at the surface of the water, during the ordinary rise and fall of the water, and for all positions of the boiler, said connection comprising a pipe which is flexible to permit movement of said float in any direction.

3. A boiler blow-off and cleaner comprising a float having an intake at the surface of the water, and an outlet connection for said float, serving to maintain said float in horizontal position at the surface of the water, during the ordinary rise and fall of the water, said connection permitting bodily up and down movement of said float.

4. A boiler blow-off and cleaner comprising a float having an intake at the surface of the water, and an outlet connection for said float, serving to maintain said float in horizontal position at the surface of the water, during the ordinary rise and fall of the water, and for different positions of the boiler, said connection being adapted to permit rocking and bodily movement of said float in any direction.

5. A boiler blow-off and cleaner for removing the scum from the surface of the water, comprising a float, means having a

- horizontal slot forming a surface intake, supported by said float, and an offtake for said means, having provisions serving to enable said means to avoid tilting and thereby maintain said slot exactly horizontal at all times during the ordinary rise and fall of the water.
6. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, and when the position of the boiler is changed.
10. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, and when the position of the boiler is changed.
15. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, and whereby said float moves bodily up and down.
20. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, and whereby said float moves bodily up and down.
25. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, and whereby said float moves bodily up and down.
30. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, said offtake comprising a pipe which is flexible to permit movement of said float and means in any direction.
35. A boiler blow-off and cleaner for removing the scum from the surface of the water, comprising a float, means having a horizontal slot forming a surface intake, supported by said float, and an offtake for said means, having provisions serving to enable said means to avoid tilting and thereby maintain said slot exactly horizontal at all times during the ordinary rise and fall of the water, said offtake permitting rocking movement of said float in any direction relative to the boiler, as well as bodily up and down motion thereof.
40. A boiler cleaner comprising an intake having a mouth for receiving the scum from the surface of the water, a float movable up and down bodily, without tilting in any direction, during the ordinary rise and fall of the water, joined to said intake for maintaining the operative position of said mouth at the surface of the water, and an offtake for discharging the scum, adapted not to interfere with said bodily movement of the float.
45. A boiler cleaner comprising an intake having a mouth for receiving the scum from the surface of the water, a float movable up and down bodily, without tilting in any direction, during the ordinary rise and fall of the water, joined to said intake for maintaining the operative position of said mouth at the surface of the water, and an offtake for discharging the scum, adapted not to interfere with said bodily movement of the float, permitting tilting of the boiler in any direction without disturbing the operative position of said mouth.
50. A boiler cleaner provided with an intake having a horizontal inlet slot, and means for automatically maintaining said slot in operative position, horizontally, at the surface of the water, during the ordinary rise and fall thereof, thereby preventing the rise and fall of the intake from causing any variation of said slot from the horizontal.
55. A boiler cleaner comprising a float, an intake pipe encircling the float, slotted horizontally to receive the scum from the surface of the water, and an offtake communicating with said pipe, said float and pipe being movable up and down with the water, and horizontal for all ordinary heights of the water.
60. A boiler cleaner comprising a float, an intake having a horizontal slot for receiving the scum from the surface of the water, rigidly connected with said float, and an offtake communicating with said intake, said float and intake being movable up and down with the water, and being exactly horizontal for all ordinary heights of the water.
65. A boiler cleaner comprising a float, an intake encircling the float, slotted horizontally to receive the scum from the surface of the water, and an offtake communicating with said pipe, said float and pipe being movable up and down with the water, and being exactly horizontal for all ordinary heights of the water, said intake being in the form of an endless pipe, a central member engaging said offtake, and hollow spider arms connecting said pipe with said member.
70. A boiler cleaner comprising a float, an intake having a horizontal slot for receiving the scum from the surface of the water, rigidly connected with said float, and an offtake communicating with said intake, said float and intake being movable up and down with the water, and horizontal for all ordinary heights of the water, said intake being in the form of an endless pipe, a central member engaging said offtake, and hollow spider arms connecting said pipe with said member.
75. A boiler cleaner comprising a float, an intake having a horizontal slot for receiving the scum from the surface of the water, rigidly connected with said float, and an offtake communicating with said intake, said float and intake being movable up and down with the water, and horizontal for all ordinary heights of the water, being movable up and down without tilting in any direction, and having an

inlet for taking the scum from the surface of the water.

18. A boiler blow-off and cleaner comprising an intake movable up and down with 5 the water, constructed and arranged to remain horizontal for all ordinary heights of the water, being movable up and down without tilting in any direction, and having an inlet for taking the scum from the surface 10 of the water, means whereby the water moves

the intake up and down bodily, and an off-take communicating with said intake.

In testimony that I claim the foregoing as my own I have hereto affixed my signature in the presence of two subscribing witnesses. 15
